UNITED STATES PATENT OFFICE

FABRICIUS COBELLIS, OF PHILADELPHIA, PENNSYLVANIA.

MANUFACTURE OF PEROXID OF HYDROGEN.

1,195,560.

Specification of Letters Patent. Patented Aug. 22, 1916.

No Drawing.

Application filed August 23, 1915. Serial No. 46,808.

To all whom it may concern:

Be it known that I, FABRICIUS COBELLIS, a subject of the King of Italy, residing at No. 1523 Green street, in the city of Philadelphia, county of Philadelphia, and State of Pennsylvania, have invented certain new and useful Improvements in the Manufacture of Peroxid of Hydrogen, of which the following is a specification.

- 10 According to my process I produce per-sulfate of ammonium by the electrolysis, at a low temperature, of a solution of ammonium bi-sulfate. To the per-sulfate thus produced additional bi-sulfate is added and the 15 solution heated under pressure whereby the per-sulfate is split up with formation of hydrogen peroxid, which is distilled off by the application of a vacuum. The remaining bi-sulfate may be used over again.
- 20 As an example of the practice of my process, I will instance the following: Take a solution of ammonium sulfate of about three pounds to the gallon, and add thereto say three pounds of sulfuric acid, producing an 25 acid solution which I will term a bi-sulfate. This solution is placed in a cell with suitable electrodes. I have found it desirable to employ a platinum anode and a lead cathode. During the electrolysis it is important to 30 keep the electrolyte at a temperature below sixty degrees F. I find that the process proceeds best at a temperature of about forty-five degrees F. Further lowering the temperature increases the resistance of the electrolyte apparently without any corresponding advantage. At a temperature over sixty degrees oxygen is lost. The cooling of the cell with its electrolyte may be accomplished in any convenient manner, as for instance, 35 by immersion of the cell in a solution of cold brine. As the electrolysis proceeds the ammonium sulfate is converted into per-sulfate. When this has been sufficiently accomplished the solution is drawn off and placed 40 in an autoclave with the addition of ammonium bi-sulfate, say about six pounds to the gallon. In the autoclave the solution is subjected to a pressure of about one hundred pounds and under this pressure is 45 heated to about 280° F., at which temperature the per-sulfate is split up with production of hydrogen peroxid combined with solution of ammonium sulfate. This mixture is then cooled down to about 150° F., the 50 pressure released and in place thereof a vacuum applied, whereupon hydrogen per-

oxid distils over and may be collected by means of a suitable still. In order to secure complete and rapid distillation I find it desirable to pass dry air or other inert gas 60 through the solution, under the reduced pressure produced by the vacuum.

It will be understood that the proportions which I have mentioned may be considerably varied. I believe that the required ammonium bi-sulfate is best produced by the use of equimolecular quantities of sulfuric acid and ammonium sulfate and to prepare this as an electrolyte, these may be dissolved in water up to 34° Baumé, at 15° C. The 70 temperature at which the formation of hydrogen peroxid takes place may vary but the higher the heat the quicker the re-action. The pressure may also be varied, but the higher the pressure the greater the yield. 75

It will also be understood that in place of producing ammonium per-sulfate by the electrolytic process which I have described, my process may be practised with employment of ammonium per-sulfate otherwise 80 produced.

Although I have described the removal of the hydrogen peroxid by distillation *in vacuo*, there are other known ways of recovering the hydrogen peroxid from the sulfate solution. 85

Having thus described my invention, I claim:

1. The process of manufacturing peroxid of hydrogen, which consists in combining in 90 solution ammonium per-sulfate and ammonium bi-sulfate, heating the solution under pressure, whereby the per-sulfate is split up with formation of peroxid of hydrogen, and subsequently removing the peroxid of hydrogen from the solution. 95

2. The process of manufacturing peroxid of hydrogen, which consists in adding ammonium bi-sulfate to a solution of ammonium per-sulfate, heating the same under 100 pressure and subsequently distilling off the peroxid of hydrogen *in vacuo*.

3. The process of manufacturing peroxid of hydrogen, which consists of converting ammonium sulfate into ammonium per-sulfate by electrolysis, heating the solution thus produced under pressure, whereby it is converted into peroxid of hydrogen, and ammonium sulfate, and distilling over the peroxid of hydrogen. 105

4. The continuous process of manufacturing peroxid of hydrogen, which consists in

electrolyzing at a comparatively low temperature, a solution of ammonium sulfate, with formation of ammonium per-sulfate; raising the temperature under pressure, whereby the per-sulfate is again converted into sulfate, and peroxid of hydrogen; distilling off the peroxid of hydrogen *in vacuo*; and again electrolyzing the sulfate solution as the first step in a repetition of the process.

10 5. The process of manufacturing peroxid of hydrogen, which consists in combining in solution ammonium per-sulfate and ammonium bi-sulfate, raising the temperature of the same under pressure, whereby the per-
15 sulfate is split up with formation of peroxid of hydrogen and distilling off the peroxid

of hydrogen *in vacuo*, accompanied by the injection of an inert gas into the solution.

6. The process of manufacturing peroxid of hydrogen, which consists in subjecting a 20 solution of a per-sulfate salt to heat under pressure, whereby it is converted into peroxid of hydrogen and the corresponding sulfate salt in solution, and distilling over the peroxid of hydrogen.

25 In testimony whereof, I have hereunto signed my name at Philadelphia, Pennsylvania, this twenty-first day of August, 1915.

FABRICIUS COBELLIS.
